CLAIM

The ornamental design for a circular saw blade as shown and described.

DESCRIPTION

FIG. 1 is a perspective view of a circular saw blade showing the claimed design;
FIG. 2 is bottom perspective view thereof;
FIG. 3 is a front elevational view thereof;
FIG. 4 is a rear elevational view thereof;
FIG. 5 is a left side elevation view thereof;
FIG. 6 is a right side elevation view thereof;
FIG. 7 is a top plan view thereof;
FIG. 8 is a bottom plan view thereof; and,
FIG. 9 is an enlarged view of area 9 shown in FIG. 1.
The broken lines depict portions of the circular saw blade that form no part of the claimed design.
